UNITED STATES PATENT OFFICE.

ANDREW A. POSIVAK, OF SOUTH BETHLEHEM, PENNSYLVANIA.

ADJUSTABLE BOOK RACK AND STAND.

1,170,326.

Specification of Letters Patent.

Patented Feb. 1, 1916.

Application filed January 4, 1915. Serial No. 326.

To all whom it may concern:

Be it known that I, ANDREW A. POSIVAK, a citizen of the United States, and residing at South Bethlehem, in the county of Northampton and State of Pennsylvania, have invented certain new and useful Improvements in Adjustable Book Racks and Stands, of which the following is a specification.

10 This invention relates to certain new and useful improvements in adjustable book rack and stand.

The primary object of the invention is to provide an article of furniture readily adjusted for use either as a table or an inclined book-holding rack while the supporting member is readily adjustably secured at the desired elevation.

20 A further object is to provide a double-leaved table top which is vertically adjustable with means for individually tilting the leaves thereof while the latter have foldable edge strips adapted for supporting a book thereon when the device is employed as a rack.

A still further object is to provide a special form of height adjusting means for the supporting member of a table or rack.

With these general objects in view and others that will appear as the nature of the invention is better understood, the same consists in the novel combination and arrangement of parts hereinafter fully described, illustrated in the accompanying drawings, and pointed out in the appended claim.

In the drawings forming a part of this application and in which like designating characters refer to corresponding parts throughout the several views, Figure 1 is a perspective view of the complete device positioned as a book-holding rack. Fig. 2 is a perspective view of the upper portion of the device looking at the under side of the supporting member positioned for use as a table top. Fig. 3 shows enlarged perspective detail views of the two parts of one of the hinges for the leaves detached, and with the said parts separated from each other. Fig. 4 is a perspective view of one of the adjusting struts for the leaves detached. Fig. 5 is a transverse vertical sectional view taken through the supporting member as illustrated in Fig. 2 and showing such member in dotted lines positioned as a book rack. Fig. 6 is a central sectional view of Fig. 5, partly in elevation and with one of the leaves removed, and Fig. 7 is a lock-

ing means for the support adjusting mechanism detached.

The supporting device herein contemplated for use as either a horizontally positioned table top or as an inclined book support or rack is mounted upon a vertical post 10 which is provided with a plurality of supporting feet 11 and may be readily moved about after the manner of a portable stand.

The support consists of a central strip leaf 12 having similar opposite side leaves 13 hingedly mounted relatively thereto by means of hinges 14 of the form illustrated in Fig. 3. A bracket 15 of substantially triangular form has its upper side 16 horizontally-positioned while the strip leaf 12 is flatly secured to the upper surface of the said side 16. The hinges 14 each consist of a strap member 17 which is secured to the under surface of the adjacent leaf 13 and a coöperating block member 18 which is secured to the under face of the bracket 80 side 16 as best illustrated in Fig. 2, and whereby, as will be apparent, the leaves 13 may be readily swung from their horizontal position in the table top formation to an inclined position for use as a book rack. 85

An adjusting strut 19 is provided for each of the leaves 13 being hinged to lugs 20 upon the under surface of the leaves while the said struts are slidably mounted through similar spaced openings 21 of a lug 22 of 90 the inclined side 23 of the bracket whereby the inclination of the leaves may be readily effected. Each of the struts 19 is provided with a terminal hook 24 on its lower edge which engages the side of its receiving opening 21 when its respective leaf 13 is horizontally positioned while a leaf spring 25 carried by the strut engages the upper side of the same opening for retaining the hook 24 in such engagement. When desired to 100 shift one of the leaves 13 from their horizontal table top position to an inclined position, the strut is shifted against its spring 25 so as to release the engagement of its hook 24 and allow the connected leaf to 105 drop of its own weight until the notch 26 in the lower edge of the strut engages the lower edge of the opening 21, and thus retains the leaf so inclined and at which time the strut will be positioned substantially 110 horizontal, as best shown in dotted lines in Fig. 5.

The opposite outer free edges of the leaves 13 are provided with book supporting strips

27 hinged thereto by means of the hinge members 28 which allow the strips 27 to swing in an arcuate path of substantially 270°. Such opposite edges of the leaves to 5 which the strips 27 are hinged are provided with receiving sockets 29 on their under sides which are adapted for the seating reception of the strips 27 when the leaves are positioned as a table, as illustrated in Figs. 2 10 and 5 and at which times, hooks 30 which are carried by the ends of the said strips are engaged with pins 31 upon the outer edges of the adjacent leaves for retaining the strips in their closed positions. When the 15 leaves are shifted to their inclined positions as book-holders, the strips 27 are released and swung to a position perpendicular to the carrying leaves as illustrated in Fig. 1, and at which time the hooks 30 are employed for 20 retaining the strips in such positions. Leaf springs 32 are mounted upon the book-engaging faces of the strips 27 having their outer ends flatly secured thereto whereby the book 33 or other member to be supported 25 is positioned flatly upon the inclined leaf and has its edges engageable by the free ends of the springs 32 for retaining the book open at any desired page thereof.

The bracket 15 has its rear side 34 provided with spaced straps 35 which surround the post 10 and by means of which straps the bracket is slidably positioned upon the post. The inner face of the post is provided with a longitudinal slot 36 adjacent its upper 35 end and a toothed rack 37 is secured in the bottom of the said slot while a gear 38 journaled in a slot 39' of the said bracket side 34 is in constant mesh with the teeth of the said rack 37. By this arrangement it will 40 be seen that whenever the bracket is vertically moved, the gear will be turned by reason of its meshing engagement with the stationary rack heretofore described.

A locking means for the gear 38 is provided of the form shown in Fig. 7 and consists of a block 39 having a single end tooth 40 shiftable transversely of the gear and engageable with the teeth thereof.

A yoke 41 is rigidly secured to the bracket 50 side 34 at a point above the gear and the block 39 is shiftable mounted within the said yoke by means of a bolt 42 carried by the block and slidably positioned through a longitudinal slot 43 in the forward side of 55 the yoke. Oppositely projecting operating rods 44 terminating in handles 45 are secured at their inner ends to the opposite sides of the block 39 and slidably project through the ends of the yoke while one of the said rods is provided with an encircling expansion spring 46 and whereby the block 60 is normally positioned with the bolt engaging the inner end of the yoke slot and

with the tooth 40 in locking engagement with the bracket gear.

65

The complete operation of the device will now be apparent as the manner of adjusting the supporting leaves has been already set forth and it will now be seen that when the locking bolt is normally positioned engaging the bracket gear, a movement imparted thereto in the direction toward the right end of the block yoke by means of the operating rods will disengage the block tooth from the gear, thus allowing the bracket and support 70 to be freely moved either up or down as desired, and during which time the block tooth is held out of engagement with the gear by means of one of the handles 45, and when the desired vertical adjustment is secured, the handle is released and the spring 46 returns the block tooth into its locked engagement with the gear, thus securing the support as positioned.

75

A serviceable device is thus provided which is designed to fulfil the objects hereinbefore enumerated, the same being capable of employment as a horizontal table top or as a single or double inclined book support.

80

While the forms of the invention herein shown and described are what are believed to be preferable embodiments thereof, it is nevertheless to be understood that minor changes may be made in the form, proportion and details of construction without departing from the spirit and scope of the invention as set forth in the appended claim.

90

What I claim as new is:—

A device of the class described comprising the combination with a post having a longitudinal side slot therein, a toothed rack secured within said slot, a bracket vertically slidable upon the said post and having its inner side provided with a slot adjacent the said post slot, a gear journaled in the said bracket slot and positioned in constant engagement with the said rack, a yoke secured to the inner side of the said bracket and having a longitudinal slot in the front side thereof terminating at substantially the center of such side, a locking block for the said gear, a bolt carried by the said block and extending through the said yoke slot, oppositely-arranged operating rods secured to the said block, and a normal positioning spring carried by one of the said rods whereby the said block is normally positioned in engagement with the said gear and with the bolt seated at the inner end of the said yoke slot.

100

In testimony whereof I affix my signature in presence of two witnesses.

ANDREW A. POSIVAK.
